Moses E. King, Inventor

UNITED STATES PATENT OFFICE.

MOSES E. KING, OF NEENAH, WISCONSIN.

ENVELOPE.

Application filed August 14, 1924. Serial No. 732,125.

To all whom it may concern:

Be it known that I, Moses E. King, a citizen of the United States, residing at Neenah, in the county of Winnebago and 5 State of Wisconsin, have invented a new and useful Improvement in Envelopes, of which the following is a specification.

My invention relates to improvements in envelopes and has for its object to provide 10 an article of this character having integral means whereby the envelope may be conveniently and securely affixed to a package when forwarding packages by parcel post, so letters of instructions may accompany the 15 goods.

A further object of the invention is to provide an envelope attachable to a package, to which access may be readily had for removing the contents thereof.

20 Another object of the invention is to provide an article of the above character which is simple and strong in construction, convenient in use and inexpensive to manufacture.

25 Other objects and advantages of the invention will be apparent during the course of the following description.

In the accompanying drawing forming a part of this specification and in which like 30 numerals are employed to designate like parts throughout the same,

Fig. 1, is a perspective view of a package with my envelope affixed thereto,

Fig. 2, is a plan view of the blank from 35 which the envelope is formed,

Fig. 3, is a front elevation of the envelope before folding the flaps,

Fig. 4 is a front elevation of the envelope closed,

40 Fig. 5, is a cross section on lines 5—5 of Fig. 4, and,

Fig. 6, is a cross section on lines 6—6 of Fig. 3.

In the drawing, wherein for the purpose 45 of illustration I have shown a preferred embodiment of my invention the letter A denotes the blank of paper from which my envelope is formed which is folded along the line B to form the front and back walls 5 and 6. The side edges of the front wall 5

are provided with longitudinally extending flaps 7 which are transversely perforated at spaced intervals, as at 8, to form the central tabs 9 which extend beyond the edges of the flaps. The portion of the flaps on each side 55 of the tabs are gummed on their under sides, so when folded around the edges of the back wall 6 they will hold the front and back walls together. The tabs are also folded around the edges of the back wall, but are 60 gummed on their outer surface, so the envelope may be securely affixed to a package 12 or the like. The upper edge of the front wall is recessed, as at 10, to facilitate the insertion and removal of the letter from the 65 envelope and is closed by the flap 11 formed integral with the upper edge of the back wall which folds down against the front wall and sealed thereto, as clearly shown in Fig. 4.

In use, it will be seen that the function of dividing the end flaps into three sections is to provide tabs for securing the envelope together and tabs for securing the envelope to a package. By reason of this construction, the envelope may be conveniently attached to the package, and when it reaches its destination may be readily detached therefrom, without affecting the tabs securing the envelope together. Its construction will insure the safety of the contents 75 and by folding the securing tabs beneath the envelope, afford protection against accidental displacement while the package is in transit.

It is to be understood that the form of my invention herewith shown and described is to be taken as a preferred example of the same and that certain changes in the shape, size and arrangement of parts may be resorted to without departing from the spirit 80 of the invention or the scope of the subjoined claim.

Having thus described my invention, I 85 claim:

An envelope formed from a single sheet of material folded upon itself to form front and back walls, longitudinal flaps extending along opposite sides of the front wall and contiguous therewith, said flaps being trans-

versely perforated at spaced intervals providing a central and end tabs, said end tabs having cement on their under face and adapted to fold over the adjacent edges of the back wall to secure the front and back walls together, said central tab being foldable over the back wall and having cement

on its upper face whereby the envelope may be secured to an object, and a closing flap formed along the upper edge of the back wall adapted to be folded over and secured to the front wall.

In testimony whereof I affix my signature.
MOSES E. KING.
